UNITED STATES PATENT OFFICE.

ALBERT BOTTUM, OF BRIDGEPORT, CONNECTICUT.

IMPROVED CHANNELING-TOOL.

Specification forming part of Letters Patent No. 40,814, dated December 8, 1863.

To all whom it may concern:

Be it known that I, ALBERT BOTTUM, of Bridgeport, in the county of Fairfield and State of Connecticut, have invented a new and useful Improvement in Channeling-Cutters for cutting channels in the soles of boots and shoes and other articles; and I do hereby declare that the following is a full, clear, and exact description of the same, reference being had to the accompanying drawings, forming a part of this specification, in which—

Figure 1 is a front view of my improved cutters. Fig. 2 is a top view of the same. Fig. 3 is a front view of the cutters and a transverse section of a shoe-sole, illustrating the operation of my invention. Fig. 4 is a transverse section of the sole, showing the form of the channel and representing it open on one side and closed on the other.

Similar letters of reference indicate corresponding parts in the several figures.

This invention consists in the combination of a straight cutter and an arc-formed cutter, so arranged relatively to each other that while the first cuts a score in the sole or other article the other cuts from within the said score a strip whose transverse section is of semicircular or segmental form, thus producing a semicircular or segment-shaped covered channel.

To enable others skilled in the art to make and use my invention, I will proceed to describe its construction and operation.

A is the straight cutter—that is to say, it has a straight or flat face like a knife-blade, which causes it to produce a straight cut, though its cutting-edge *a* is curved and brought to a point, as shown in Fig. 2. B is the arc-formed cutter—that is to say, its edge is curved in such direction as to produce an arc-formed cut. These cutters are firmly secured together by a screw, C, passing through one and screwing into the other, or by other suitable means, in such man-

ner that the first one extends across the arc of the second one in the form of a cord to said arc, as is illustrated by Fig. 1, and are to be so arranged in a cutting-machine or otherwise that while the first one cuts an oblique score, *b*, in the sole D or other article, the second one cuts from within the said score the semi-circular or segment-shaped strip *c*, (shown in the transverse section, Fig. 3,) so that when the said strip is removed it leaves the semi-circular or segment-shaped channel *d* shown in Fig. 4.

This combination of cutters, while it cuts without choking, and much more freely and easily than the combination of a straight cutter and a ring-shaped tubular one, cuts a channel of the most desirable form for the soles of boots and shoes, and which, though it presents a wide opening for the reception of the sewing when the lap *e* left above the score *b* is turned back, as shown at the right-hand side of Fig. 4, leaves no ridge over the sewing when the lap *e* is closed, as shown at the left-hand side of the same figure.

The straight cutter is represented as arranged in front of the curved one. The arrangement might be reversed; but I consider that represented to be the best, as it affords greater facility for turning the corners of the soles, more especially those of square-toed boots and shoes.

What I claim as my invention, and desire to secure by Letters Patent, is—

The combination of the straight cutter A and the arc-formed cutter B, for cutting a score and a channel within it of the form substantially as herein specified.

ALBERT BOTTUM.
